UNITED STATES PATENT OFFICE.

JAMES H. MILLSPAUGH, OF GUTHRIE, OKLAHOMA.

SWITCH-OPERATING MEANS.

1,179,547.

Specification of Letters Patent. Patented Apr. 18, 1916.

Application filed May 24, 1915. Serial No. 30,161.

To all whom it may concern:

Be it known that I, JAMES H. MILLSPAUGH, a citizen of the United States, residing at Guthrie, in the county of Logan and State of Oklahoma, have invented certain new and useful Improvements in Switch-Operating Means, of which the following is a specification, reference being had to the accompanying drawings.

This invention relates to certain improvements in switch operating means and has relation more particularly to a construction whereby the device may be operated from the rolling stock; and it is an object of my invention to provide novel and improved means of this general character wherein the same comprises a minimum of parts and whereby the switch is adjusted into either an open or closed position with convenience and facility.

The invention consists in the details of construction and in the combination and arrangement of the several parts of my improved switch operating means whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view in top plan illustrating a switch operating means constructed in accordance with an embodiment of my invention; Fig. 2 is an enlarged view, partly in elevation and partly in section, illustrating the rotatably supported plate herein included together with its concomitant parts; Fig. 3 is a sectional view taken substantially on the line 3—3 of Fig. 1, looking in the direction of the arrow; Fig. 4 is a fragmentary view, partly in elevation and partly in section, illustrating the mechanism carried by the rolling stock for operating my improved switch operating means; and Fig. 5 is a fragmentary view in top plan illustrating a modified means for operating the rock plate.

As disclosed in the accompanying drawings, A denotes a track-way having extending therefrom the branch B, the branch B be-

ing provided with the pivoted tongues C coacting with the rails of the track-way A in a conventional manner. Operatively engaged with the tongues C are the inwardly directed arms 1, each of which being herein disclosed as comprising two sections capable of longitudinal adjustment, as indicated at 2, and with the inner extremities of said arms operatively engaged with the plate 3. The plate 3 is rotatably supported at its axial center through the medium of the pivot pin 4 by the plate 5 suitably secured to the ties of the track-way A. The plate 3 may be of any configuration desired but as herein disclosed is substantially rectangular in form with its longitudinal diameter disposed obliquely across the track-way A and the opposite extremities of said plate are provided with the transversely disposed slots 6 of predetermined length, each of said slots being provided with the inwardly diverging extensions 7.

Positioned within each of the slots 6 is a roller 7a carried by the inner extremity of a plunger 8 disposed longitudinally of the track-way A and having its opposite extremity operatively engaged with the lever 9 disposed transversely of the track-way and pivotally supported adjacent one of the rails thereof so as to be engaged by an operating member N depending from the rolling stock. As herein disclosed, the operating member comprises a bar 10 mounted for vertical movement and normally maintained at the limit of its upward movement by the expansible member 11. One face of the bar 10 is provided with the rack 12 with which is in mesh the segmental rack 14 adapted to be rotated by the crank 15 in order to bring the lower extremity of the bar 10 in a position to engage the lever 9. The engaging extremity 16 of the bar is pivotally engaged with the bar proper and is normally maintained in longitudinal alinement with the bar under the influence of the spring 17. By this it will be readily perceived that when the lever 9 has been sufficiently moved to properly rock the plate 3, the engaging extremity 16 will readily pass the lever or ride over any other obstruction with which it may come in contact. As the plunger 8 is moved inwardly, it will contact with an inner edge of an extension and thus rock the plate 3, in a manner which is believed to be self-evident, and will automatically return

to engagement with an outer edge of an extension through the medium of the retractile members 18 positioned at opposite sides of the plunger and having adjacent extremities 5 suitably secured thereto with the opposite extremities anchored to a tie of the track structure A or other stationary supports.

In order that proper signal may be given as to the condition of the switch, I mount to 10 one side of the track-way A the rotatable signal S, the shaft 19 of which being provided with a rock arm 20 operatively engaged with the plate 3 through the medium of the arm 21.

15 In lieu of the lever 9 hereinbefore referred to, the crank shaft 22 may be employed and such crank shaft is provided with an up-standing crank arm 23 adapted to be engaged by the operating mechanism which 20 is substantially identical to that described relative to the bar 10 and its concomitant parts, except that such bar is horizontally disposed.

From the foregoing description, it is 25 thought to be obvious that switch operating means constructed in accordance with my invention is of an extremely simple and comparatively inexpensive nature and is particularly well adapted for use by reason 30 of the convenience and facility with which it may be assembled, and it will also be obvious that my invention is susceptible of some change and modification without material departure from the principles and 35 spirit thereof and for this reason I do not wish to be understood as limiting myself to the precise arrangement and formation of the several parts herein shown in carrying out my invention in practice.

40 The plate 3 is provided with an arcuate slot 24 through which extends a pin 25 or the like projecting upwardly from the plate 5 and by this arrangement it will be readily perceived that the axial movement of the 45 plate 3 in either direction is effectively controlled. I also find it of advantage to have coacting with the plate 3 the retractile member 26 which serves as a rebound member, said spring being herein disclosed as having 50 one extremity suitably anchored to a tie, while the opposite extremity is anchored to the plate 3 at a point beyond the axial center thereof and is adapted to be thrown on opposite sides of the dead center to resili- 55 ently hold the plate 3 in its end positions. I also find it of advantage to provide the plate 3 inwardly of each of the slots 6 and adjacent the extremities thereof with the upstanding lugs 27 which serve to assure 60 the roller 7^a of the plunger 8 moving within the proper extension 7. It is to be particularly noted in Fig. 2 that the lugs 27 are tapered one toward the other so that when the plungers are in normal position the inner 65 ends thereof are positioned adjacent the ab-

rupt shoulders of the lugs whereby it will be perceived that the proper travel of the rollers 7^a is assured. When the plate 3 has been turned through the medium of one of the plungers, the second plunger will be 70 carried by the adjacent lug a slight distance when it will slide by said lug and a swing 18 will carry it over the second lug 27 and position it beyond the abrupt shoulder thereof. 75

I claim:

1. In combination with the movable tongue of a switch, a plate mounted for rotary movement and provided with a slot, an arm pivotally engaged with the tongue and 80 the plate, a plunger mounted for substantial endwise movement and having one extremity extending within the slot of the plate, automatic means for imparting movement to the plunger in a direction away 85 from the plate, and means coacting with the plunger for imparting movement thereto in a direction toward the plate whereby said plate is rotated.

2. In combination with the movable tongue of a switch, a plate mounted for rotary movement and provided with a slot, an arm pivotally engaged with the tongue and the plate, a plunger mounted for substantial endwise movement and having one 95 extremity extending within the slot of the plate, automatic means for imparting movement to the plunger in a direction away from the plate, and means coacting with the plunger for imparting movement thereto in 100 a direction toward the plate whereby said plate is rotated, the slot of the plate being provided with inwardly disposed diverging extensions.

3. In combination with the movable tongue of a switch, a plate mounted for rotary movement and provided with a slot, an arm pivotally engaged with the tongue and the plate, a plunger mounted for substantial endwise movement and having one extremity 105 extending within the slot of the plate, automatic means for imparting movement to the plunger in a direction away from the plate, and mechanism carried by the rolling stock 110 coacting with the plunger for imparting movement thereto in a direction toward the plate whereby said plate is rotated in one direction. 115

4. In combination with the movable tongue of a switch, a plate mounted for rotary movement and provided with a slot, an arm pivotally engaged with the tongue and the plate, a plunger mounted for substantial endwise movement and having one extremity 120 extending within the slot of the plate, automatic means for imparting movement to the plunger in a direction away from the plate, means coacting with the plunger for imparting movement thereto in 125 a direction toward the plate whereby said 130

plate is rotated, and means carried by the plate coacting with the plunger for controlling the lateral movement of the plunger.

5. In combination with the movable tongue of a switch, a plate mounted for rotary movement and provided with a slot, an arm pivotally engaged with the tongue and the plate, a plunger mounted for substantial endwise movement and having one extremity extending within the slot of the plate, automatic means for imparting movement to the plunger in a direction away from the plate, means coacting with the plunger for imparting movement thereto in a direction toward the plate.
- 10 5. In combination with the movable tongue of a switch, a plate mounted for rotary movement and provided with a slot, said slot being provided with inwardly diverging extensions, a plunger mounted for substantial endwise movement and having one extremity extending within the slot of the plate, lugs projecting from the plate inwardly of the slot and adjacent the extensions, each of said lugs serving as a guide 40 to assure movement of the plunger within the adjacent extension of the slot, automatic means for imparting movement to the plunger in a direction away from the plate, means coacting with the plunger for imparting movement thereto in a direction toward the plate, and a retractile member coacting with the plate.
- 15 6. In combination with the movable tongue of a switch, a plate mounted for rotary movement and provided with a slot, said slot being provided with inwardly diverging extensions, a plunger mounted for substantial endwise movement and having one extremity extending within the slot of the plate, lugs projecting from the plate inwardly of the slot and adjacent the extensions, each of said lugs serving as a guide 45 to assure movement of the plunger within the adjacent extension of the slot, automatic means for imparting movement to the plunger in a direction away from the plate, means coacting with the plunger for imparting movement thereto in a direction toward the plate, and a retractile member coacting with the plate.
- 20 6. In combination with the movable tongue of a switch, a plate mounted for rotary movement and provided with a slot, said slot being provided with inwardly diverging extensions, a plunger mounted for substantial endwise movement and having one extremity extending within the slot of the plate, lugs projecting from the plate inwardly of the slot and adjacent the extensions, each of said lugs serving as a guide 50 to assure movement of the plunger within the adjacent extension of the slot, automatic means for imparting movement to the plunger in a direction away from the plate, means coacting with the plunger for imparting movement thereto in a direction toward the plate, and a retractile member coacting with the plate.
- 25 7. In combination with the movable tongue of a switch, a plate mounted for rotary movement and provided with a slot, said slot being provided with inwardly diverging extensions, a plunger mounted for substantial endwise movement and having one extremity extending within the slot of the plate, lugs projecting from the plate inwardly of the slot and adjacent the extensions, each of said lugs serving as a guide 55 to assure movement of the plunger within the adjacent extension of the slot, automatic means for imparting movement to the plunger in a direction away from the plate, means coacting with the plunger for imparting movement thereto in a direction toward the plate, and a retractile member coacting with the plate.

In testimony whereof I hereunto affix my signature in the presence of two witnesses. 55

JAMES H. MILLSPAUGH.
